US00D964270S

(12) **United States Design Patent** (10) Patent No.: **US D964,270 S**
(45) Date of Patent: ** Sep. 20, 2022

(54) **BATTERY**

(71) Applicant: **MAKITA CORPORATION**, Anjo (JP)

(72) Inventors: **Shinsuke Okuda**, Anjo (JP); **Tatsuya Nagahama**, Anjo (JP)

(73) Assignee: **MAKITA CORPORATION**, Anjo (JP)

(**) Term: **15 Years**

(21) Appl. No.: **29/828,458**

(22) Filed: **Feb. 25, 2022**

Related U.S. Application Data

(63) Continuation of application No. 29/725,483, filed on Feb. 25, 2020, now Pat. No. Des. 945,959.

(57) **CLAIM**

The ornamental design for a battery, as shown and described.

DESCRIPTION

FIG. 1 is a front, top, left side perspective view of a battery showing our new design;

FIG. 2 is a rear, top, right side perspective view thereof; FIG. 3 is a top plan view thereof; and,

FIG. 4 is a left side elevational view thereof.

The broken lines depict portions of the battery that form no part of the claimed design. The dot-dash broken lines represent a boundary between claimed portions and unclaimed portions of the battery and form no part of the claimed design.

1 Claim, 4 Drawing Sheets
